CLAIM

The ornamental design for an essential oil diffuser, as shown and described.

DESCRIPTION

FIG. 1 is a front elevational view of an essential oil diffuser showing my new design;

FIG. 2 is a rear elevational view thereof;

FIG. 3 is a right elevational view thereof;

FIG. 4 is a left elevational view thereof;

FIG. 5 is a bottom plan view thereof;

FIG. 6 is a top perspective view thereof; and,

FIG. 7 is a top plan view thereof.

In the drawings, the broken lines depict portions of the essential oil diffuser that form no part of the claimed design.
